UNITED STATES PATENT OFFICE.

THOMAS MOORE JAMISON, OF MEMPHIS, TENNESSEE.

DESIGN FOR A LAMP-FIXTURE.

SPECIFICATION forming part of Design No. 35,834, dated April 1, 1902.

Application filed March 1, 1902. Serial No. 96,345. Term of patent 3½ years.

To all whom it may concern:

Be it known that I, THOMAS MOORE JAMISON, a citizen of the United States, residing at Memphis, in the county of Shelby and State of Tennessee, have invented and produced a new and original Design for Lamp-Fixtures; and I do hereby declare the following to be a full, clear, and exact description of the same, reference being had to the accompanying specification, forming a part thereof.

This invention relates to a design for a lamp-fixture of unique and pleasing appearance, as shown in the accompanying facsimile drawing, which is an elevation thereof.

The fixture is of oblong form and comprises an upper and a lower portion. The upper part is of loop form and comprises parallel side rods or members 1, a lower cross-rod 2, and an upper member 3, of arched form, having a central body 4, enlarged or swelled at its middle and provided with terminal enlargements. The lower part has the appearance of a frame and comprises side members outwardly curved at 5 and inwardly curved

near their lower ends, as at 6, a lower member 7, and elbows 8, connecting the parts 6 and 7. The upper ends of the side members are curved inward, at 9, and bodies 10 join the proximal ends of the elements 1, 2, and 9 and are swelled between their ends and have a middle and terminal enlargements at the points of juncture with the said elements. A body 11 is located central of the member 7 and has a pendant 12 and a lateral extension 13. Scrolls 14 are located in the incurves 6 and blend with the entire design to produce a pleasing, attractive, and ornamental appearance.

Having thus described the invention, what is claimed as new is—

The design for a lamp-fixture, substantially as herein shown and described.

In testimony whereof I affix my signature in presence of two witnesses.

THOMAS MOORE JAMISON. [L. S.]
